UNITED STATES PATENT OFFICE.

HERMANN ARNDT, OF BERLIN, GERMANY, ASSIGNOR TO SIEMENS & HALSKE, AKTIEN-
GESELLSCHAFT, OF SIEMENSSTADT, NEAR BERLIN, GERMANY, A CORPORATION
OF GERMANY.

TRAIN-STOP-CONTROL DEVICE.

Application filed November 17, 1926, Serial No. 143,884, and in Germany November 21, 1925.

My invention relates to a method for preventing railroad trains or cars from running past stop signals.

It is already common to prevent the running past stop signals by transmitting the signal automatically to the train or car by means of levers, contacts or magnetic means which automatically effect the application of the brakes or in the case of electric railways 10 the interruption of the supply of current and prevent the release of the brakes after the stop or produce all these results simultaneously. Such train safety devices must be so designed that after the train has been 15 brought to a stop, and after the cause for the stop is removed, the safety device can be returned into the position of rest and the train be started again.

To increase the safety still further such 20 train control devices are, according to my invention, so designed that after restarting the train can only attain a safe predetermined speed beyond which the train-stop device is rendered automatically operative again by 25 a device controlled by the speed of the train. This result may according to my invention be attained, for instance, by causing the armature of a supervising control relay to drop off simultaneously with the operation 30 of the train-stop device when encountering a stop signal, which armature, however, cannot at once be returned into the position of rest after the train is started again. This dropped off armature of the relay then connects the stop-device with circuits, the closing or opening of which is controlled by a 35 centrifugal governor or a similarly acting device, so that as soon as a predetermined speed is exceeded the stop device is actuated 40 independently. Preferably, the relay is connected with the lever or the like controlled by the track signal in such a manner that it becomes operative under all circumstances, even when the train has duly stopped in 45 front of the signal. The train-stop device is in such a case usually reset later in order to resume travel and sometimes it may be even rendered inoperative altogether from the engineer's cab in well known manner when the 50 engineer is permitted to travel past the stop signal. In all cases, whether the train has been stopped or permitted to overrun the stop signal, it is necessary to travel carefully when starting again, a caution which, however, is not always observed by the engineer.

The resetting of the control relay to the original state may then be effected at certain points along the track by the track guard after the lapse of a certain time. In order to prevent the premature and promiscuous 60 resetting it may be made dependent upon the running off of a clockwork or by providing lead seals which the track guard alone is permitted to break.

In the drawing affixed hereto an embodiment of my invention is illustrated partly 65 diagrammatically and partly in perspective view.

In this diagram 30 is the train-stop device located along the track which, when the "stop" signal is set at the semaphore mast S, takes the position shown in full lines, while it is in the position 31 indicated in dotted lines when the "proceed" signal is set. 32 is the actuating lever, which may be located 70 upon the roof of the engine and which when the train-stop device 30 is at "stop" is thrown in counter clockwise direction. It thereby carries the locking pawl 33 along 75 against the resistance of the spring 34, so that the controller drum 35, in the recess 36 of which pawl 33 is normally located, now can turn in the direction of the arrow shown, under the action of the tension spring 37. Upon the controller drum are provided 80 copper segments 8, 9 and 10 over which glide the contact fingers 141, 142, 143, 144, 145 and 146. 38 represents the electrically controlled brake valve which, when energized causes the application of the brakes, 85 in well known manner. 39 is the electrically controlled brake release valve which when energized effects the release of the brakes in a similar manner. 40 is the circuit breaker which bridges over the contacts 42 and 43 in the line 44 leading across the controller to the motors, in well known manner (it is assumed in the present case that the train is propelled by electric motors). During the train travel the lever 41 is maintained in the position shown by a locking pawl 45, in which position it closes the contacts 42, 43. The locking pawl 45 is a double-armed lever, the second arm of 90 which is connected with an iron core 46 which is attracted when the solenoid 47 is traversed by current, and thereby operates the locking pawl 45 which then releases the lower end of the contact lever 41. This lever can now rock in clockwise direction 95 100 105 110

under the influence of the spring 48, whereby the line 44 is interrupted and the motors come to a stop. 49 shows the hand brake switch drum for the engineer in developed state. Upon the drum segments 50 slide the contact fingers 51, 52 and 53, which are in the position 54 on the drum during braking, in the position 55 when travelling and in the position 56 when the brakes are released. In order to energize the brake release valve 39, or the brake valve 38 and the solenoid 47 for cut-out switch 42, 43 in accordance with the position of the hand controller 49 as well as in dependency upon the position of controller 35, special lines 57, 58, 59 and 60 are provided at the roof of the car or engine which lines are coupled with the corresponding lines of the adjacent car by plug and socket connections 70, 71 or the like. The line 60 is fed from the trolley wire 73 through the trolley 27. The brake release valve 39 is connected at one terminal with the line 59 and at the other with the ground at 74, while the brake valve 38 is connected at one terminal with the line 57 and at the other terminal with the ground at 75. When the engineer applies the brakes himself, he sets the switch drum 49 into the finger contact position 54. The brake valve 38 then receives current over the following circuit: trolley wire 73, arm 27, lines 60 and 76, contact finger 51, segment 50, contact finger 52, line 77, valve 38, ground 75. When releasing the brakes by means of the hand drum 49, the latter is set into contact position 56 where the brake releasing valve 39 receives current along the following circuit: trolley line 73, arm 27, line 76, fingers 51, 53, line 104, contact 97, line 155, contact 9 on drum 35, lines 58, 59, valve 39, ground 74. If the stop lever 32, which normally holds drum 35 in the position shown, is swung aside by the train stop 30 and the controller drum 35, as described above, is turned in the direction of the arrow shown, the line to the brake release valve is interrupted at the drum contact 9 and simultaneously the line to the brake valve 38 closed over the following circuit: trolley line 73, arm 27, lines 60, 78, finger 145, contact 8, finger 146, lines 80, 57, valve 38, ground 75. Simultaneously the solenoid 47, which by means of the armature 46 can interrupt the line 44 and thus effect the cutting off of the operating current, receives current by way of the following circuit: lines 73, 27, 78, branch 104', contact finger 141, contact 10, finger 142, line 82, solenoid 47, ground 83. In this way the stopping of the train motors and the application of the brakes is effected in a well known manner.

According to my invention an arm 84 carrying the contact 4 is fixed on the shaft 65 of lever 32. In the position of the lever 32

shown, this arm 84 bridges over the contact fingers 85 and 86, so that the relay 2 arranged according to my invention receives current across the following circuit: lines 73, 27, 78, branch line 87, contacts 85, 4, 70 86, line 1, contact 88 made by the armature 3 of the relay 2, relay winding 2 and ground 89.

With one axle 11 of the train is connected a centrifugal governor 12 which may be driven in any suitable manner, for instance by bevel wheels 90, and which when the speed of the train increases carries the contact arm 13 upwards, whereby it interrupts on the one hand the connection between the contacts 91 and 92, and on the other hand closes the connection between the contacts 93, 94, 95 and 96. When actuating lever 32 is in normal position shown the relay 2 receives current in the manner previously stated and maintains its armature 3 attracted which in turn keeps the relay energizing line closed at the contact 88 and by the contacts 97 also the line which leads to the brake release valve across the contact 9 of the controller drum previously traced. When the lever 32 is moved from normal position by the track stop 30 and the relay 2 is deenergized by the breaking of the contact 4, its armature 3 drops off, interrupts the circuit of the contacts 88 and 97, and connects by means of the contacts 98 and 99 the brake release valve 39, the brake valve 38 and the solenoid 47 of the cut-out switch 40 with the aforesaid contacts 91 to 96 which are connected with the centrifugal governor as will presently be described. If after the train has been brought to a stop the lever 32 is returned by spring 34 into its normal position shown, the controller 35, when returned into normal position shown by means of handle 100 against spring 37, can be locked again in this position by pawl 33 and the engineer is able to operate the hand controller drum 49 in the normal way described and to proceed with the train. The arrangement of armature 3 of relay 2, as shown, is such that when once released by relay 2, it is held in released position by means of a spring actuated pawl 103 until reset by auxiliary means to be described later. Therefore, with the aforementioned hand controller operation of the train, armature 3 is still in the dropped off position but the place of the contact 97 which normally closes the brake release line has now been taken by the contacts 91, 92 and lever 13 at the centrifugal regulator owing to the slow speed of the train. Thus when the engineer has set his hand controller 49 into the position 56, the brake release valve 39 is under slow speed conditions energized by the following circuit: trolley line 73, arm 27, lines 60 and 76, fingers 51, 53, line 104, contact 91, lever 13, contact 92, line 155, 130

fingers 144, 143, and contact 9 on drum 35, lines 58, 59, valve 39 and ground 74. Although the contact 4 controlled by arm 84 has been closed again, the relay 2 receives

5 no current for the time being since the armature contact 88 is still broken. The continuation of the travel is therefore possible so long as the speed of the train remains low. If the speed exceeds a definite value the 10 lever 13 is raised by the centrifugal governor 12, interrupts the line to the brake release valve and simultaneously connects the contacts 93, 94, 95 and 96, so that the brake valve and the solenoid 47 controlling the cut- 15 out switch 40 now receive current across the contacts 93, 94, 95 and 96 and the contacts 98, 99 provided upon the dropped off armature 3 of the relay 2, in a similar manner as described with reference to the controller 35, 20 solenoid 47 receiving current over the following circuit: lines 73, 27, 78, branches 118 and 101, contact 99, line 18, contact 95, lever 13, contact 96, line 19, branch 119, solenoid 47 and ground 83. The brake valve 38 re- 25 ceives current by way of the following circuit: lines 73, 27, 78, branch 118, branch 102, contact 98, line 14, contact 93, lever 13, contact 94, line 15, lines 81, 57, valve 38 and ground 75. 30 Only when the armature 3 has been returned into the normal position shown the brake valve 38, the brake release valve 39 and the solenoid 47 become again independent of the centrifugal governor 12. The re- 35 turn of the armature 3 into the normal position, i. e. the attracted position, may be effected either by hand or automatically after a predetermined time by any suitable retarding means known in the art. In the 40 present example hand operated means are shown. For this purpose I provide a locking pawl 103 which locks armature 3 in the dropped position. This locking pawl is enclosed in a box 115, which may be sealed as 45 shown at 116, and only the station master may be authorized to break the seal, and to reset armature 3 into attracted position, in which it is held, immediately contact 88 is closed and solenoid 2 is energized. There- 50 by also contact 97 is closed and thus the control of the system is restored to the engineer's hand controller 49 for normal operation.

It should be noted from the drawing that 55 it is possible, even if track lever 30 stands in "stop" position, to keep the controller drum in the position illustrated by holding the reset lever 100 and thus the drum against the tension of spring 37, if it is desired intentionally to travel past a set stop signal, for instance with permission of the station master, so that the controller drum is not rotated when the lever 32 is turned aside by stop 30. The contact 4 is nevertheless inter- 60 rupted by its arm 84 swinging with lever

32, so that also in this case the centrifugal governor is connected with the system and put into control for the purpose above described.

Various modifications and changes may be 70 made without departing from the spirit and the scope of the invention, and I desire, therefore, that only such limitations shall be placed thereon as are imposed by the prior art. 75

I claim as my invention:

1. A device for automatically stopping a train by a track signal, comprising a stopping device on the train and a stop actuating device normally controllable by the engineer, an independent automatic stop actuating device, and means controlled by the track signal for actuating said automatic device, means controllable by the engineer for resetting said automatic device to inoperative position and for maintaining it in said position if desired, a speed responsive second automatic stop actuating device, independent of the first automatic device and of the engineer's device, adapted to actuate the stopping device only when a desired train speed limit is exceeded, and a supervising device on the train also controlled by the track signal, but out of the engineer's control, for placing said second automatic device in controlling position, permitting the engineer to exercise the train control at will so long as the train speed remains within the desired speed limit. 90

2. A device for automatically stopping a 100 train by a track signal, comprising a stopping device on the train and a stop actuating device normally controllable by the engineer, an independent automatic stop actuating device, and means controlled by the track signal for actuating said automatic device, means controllable by the engineer for resetting said automatic device to inoperative position and for maintaining it in said position if desired, a governor controlled 105 second automatic stop actuating device, independent of the first automatic device and of the engineer's device, adapted to actuate the stopping device only when a desired train speed limit is exceeded, and a supervising device on the train also controlled by the track signal, but out of the engineer's control, for placing said second automatic device in controlling position, permitting the engineer to exercise the train control at will 110 so long as the train speed remains within the desired speed limit. 115

3. A device for automatically stopping a 120 train by a track signal, comprising a stopping device on the train and a stop actuating device normally controllable by the engineer, an independent automatic stop actuating device, and means controlled by the track signal for actuating said automatic device, means controllable by the engineer for re- 125

setting said automatic device to inoperative position and for maintaining it in said position if desired, a speed responsive second automatic stop actuating device, independent of the first automatic device and of the engineer's device, adapted to actuate the stopping device only when a desired train speed limit is exceeded, and a supervising relay energized under normal train operation, but de-energizable by the track signal and being out of the engineer's control, for placing, when de-energized, said second automatic device in controlling position, permitting the engineer to exercise the train control at will so long as the train speed remains within the desired speed limit.

4. A device for automatically stopping a train by a track signal, comprising a stopping device on the train and a stop actuating device normally controllable by the engineer, an independent automatic stop actuating device, and means controlled by the track signal for actuating said automatic device, means controllable by the engineer for resetting said automatic device to inoperative position and for maintaining it in said position if desired, a speed responsive second automatic stop actuating device, independent of the first automatic device and of the engineer's device, adapted to actuate the stopping device only when a desired train speed limit is exceeded, and a supervising device on the train also controlled by the track signal, but out of the engineer's control, for placing said second automatic device in controlling position, permitting the engineer to exercise the train control at will so long as the train speed remains within the desired speed limit, and means out of the engineer's control for resetting said supervising device to normal to return said second automatic device to inoperative position.

5. A device for automatically stopping a train by a track signal, comprising a stopping device on the train and a stop actuating device normally controllable by the engineer, an independent automatic stop actuating device, and means controlled by the track signal for actuating said automatic device, means controllable by the engineer for resetting said automatic device to inoper-

ative position and for maintaining it in said position if desired, a speed responsive second automatic stop actuating device, independent of the first automatic device and of the engineer's device, adapted to actuate the stopping device only when a desired train speed limit is exceeded, and a supervising relay energized under normal train operation, but de-energizable by the track signal and being out of the engineer's control, for placing, when de-energized said second automatic device in controlling position, permitting the engineer to exercise the train control at will so long as the train speed remains within the desired speed limit, and means out of the engineer's control for locking said relay in de-energized condition.

6. A device for automatically stopping a train by a track signal, comprising an electrically energized stopping device on the train, an engineer's hand controller and associated circuits for normally actuating said stopping device, an automatic controller and its associated circuits normally inoperative and operated by the track signal for actuating said stopping device independently of the engineer's controller, means controllable by the engineer for resetting said automatic controller to inoperative position and for maintaining it in said position if desired, a governor controlled contact device and associated circuits adapted to energize said stopping device independently of the engineer's and of said automatic controller, but only when a desired train speed limit is exceeded, and a supervising relay on the train out of the engineer's control and being energized under normal train operation, but de-energizable by the track signal, said relay having control contacts and associated circuits for maintaining when energized, said hand controller and said automatic controller in complete control of the stopping device, and for switching when de-energized, said governor controlled contact device in parallel with said engineer's controller, thereby giving the engineer limited train control subject to the desired speed limit, and means out of the engineer's control for locking said relay in de-energized condition.

In testimony whereof I affix my signature.
HERMANN ARNDT.
